UNITED STATES PATENT OFFICE.

JOHN K. FURST, OF NEW CASTLE, PENNSYLVANIA, ASSIGNOR TO PENNSYLVANIA
ENGINEERING WORKS, OF NEW CASTLE, PENNSYLVANIA, A CORPORATION OF
PENNSYLVANIA.

JACK-CAR.

Specification of Letters Patent. Patented Dec. 18, 1917.

1,250,840.

Application filed March 12, 1917. Serial No. 154,236.

To all whom it may concern:

Be it known that I, JOHN K. FURST, a citizen of the United States, residing at New Castle, Lawrence county, Pennsylvania, have invented a new and useful Improvement in Jack-Cars, of which the following is a full, clear, and exact description, reference being had to the accompanying drawings, forming part of this specification, in which—

Figure 1 is a plan view, with a portion broken away, of a jack car embodying my invention.

Fig. 2 is a section on the line II—II of Fig. 1.

Fig. 3 is an end elevation of a car, also illustrating, in dotted lines, one use to which the car is specially adapted, and

Fig. 4 is a detail view of one form of slip gear which may be employed.

My invention has relation to jack cars, and is designed to provide a jack car of simple, convenient, strong, and serviceable character, capable of handling heavy loads, and which is adapted for a variety of purposes.

The nature of my invention will be best understood by reference to the accompanying drawings, in which I have shown the preferred embodiment thereof, and which will now be described, it being premised, however, that various changes can be made in the details of construction, arrangement and combination of the several parts without departing from the spirit and scope of my invention as defined in the appended claims.

In these drawings the numeral 2 designates the wheels, 3 the truck frame, and 4 the platform of a movable car, which may be in general of any usual or suitable construction.

The platform 4 is provided with a central hollow cylindrical post 5 rising therefrom and on which is revolvably mounted a sleeve member 6. This sleeve member is provided with a bottom flange 7 having bevel gear teeth 8 which are adapted to mesh with the corresponding teeth of a pinion 9 carried by a shaft 10 adapted to be driven through suitable gear 11 by a pinion 12 on the armature shaft of an electric motor 13. This motor is shown as mounted upon one end portion of the platform 4. The sleeve member 6 at its upper portion is provided

with a nut 14 fixedly secured thereto and having its thread engaging the thread of a vertically movable lifting screw 15. The screw 15 has revolvably mounted upon its upper end portion a load-carrying plate 16. Preferably, ball bearings 17 are interposed between the plate 16 and the upper end of the screw 15 and also between the lower end of the sleeve member 6 and its bearing on the platform 4. 18 designates a working platform arranged below the load-carrying plate 16, and to which the latter is connected by the depending struts or columns 19. The platform 18 has the depending skirt portion 20 which surrounds the sleeve member 6, and which, when the parts are in their lowered position, rests upon the car platform 4. This skirt portion 20 is cut away at one side, as shown at 21 to receive the motor 13 and the driving gear therefrom to the sleeve member 6. As the platform 18, together with the load-carrying plate 16 may be turned to a considerable extent when raised, in which case the cut away portion 21 would not register with the motor and driving connections when the parts are again lowered, I provide the platform 4 with the raised and curved guard member 22. If the parts are lowered after having been rotated, the uncutaway portion 85 of the skirt 20 will contact with this guard member, thus preventing injury to the motor and gearing, and causing the platform to be turned until the cutaway portion is brought into proper position to fit down 90 over the motor and gearing. 23 designates a dirt protecting casing for the bevel gearing, and 24 is an inclosing casing for the lower part of the screw 15. This casing 24 will preferably be filled with a suitable 95 lubricant.

25 is a key carried by the post 6 and engaging a vertical key-way in the screw 15, to prevent turning of the latter.

The operation will be readily understood. 100 When the motor 13 is energized, the sleeve member 5 and nut 14 are thereby rotated, causing the screw 15 to move upwardly or downwardly, according to the direction of rotation, and thereby raising or lowering the 105 load-carrying plate 16, and the working platform 18.

In Fig. 3 I have illustrated one of the uses to which the jack car is well adapted; viz., the putting in place and removal of 110

a converter bottom A. This bottom is placed upon the load-carrying plate 16 and is raised into position and held by the jack while being secured in place. In work of this 5 character it is desirable to provide some means whereby the upward movement of the load-carrying plate may be automatically checked before too great pressure is brought upon the converter bottom and converter.

10 While it is desirable that the converter bottom should be pressed firmly to its seat against the converter, yet undue pressure must, of course, be prevented. This may be accomplished by providing one of the 15 gear members between the motor armature and the gear flange 7 with any suitable slip connection with its shaft. In Fig. 4 I have shown the gear member 11 as having a split hub portion 11^a which can be clamped with any desired degree of pressure upon the 20 shaft 10. If this pressure is exceeded, the gear will automatically slip on the shaft, and thus prevent further upward movement of the screw 15 and the parts actuated 25 thereby.

My invention provides a jack car adapted to the handling of heavy loads. This car is simple in construction, and may be simply and conveniently operated.

30 I claim:

1. A movable car, a nut-carrying member rotatably mounted on said car, a vertically movable screw arranged to be actuated by the nut, a load-carrying plate rotatably 35 mounted on the screw, and a working platform arranged below and movable with the load-carrying plate, substantially as described.
2. A movable car, a nut-carrying member rotatably mounted on said car, a vertically movable screw arranged to be actuated by the nut, a load-carrying plate rotatably 40 mounted on the screw, and a working platform arranged below and movable with the load-carrying plate, there being a plurality 45 of load-distributing struts or posts connecting the load-carrying plate and the platform, substantially as described.
3. The combination of a movable car, a 50 nut rotatably mounted on said car, a ver-

tically movable screw post actuated by the nut, a motor and gearing for actuating the nut, a load-carrying plate rotatably mounted on the screw, and a working platform suspended from the load-carrying plate, said 55 platform having a depending skirt provided with a cut away portion adapted to fit over the nut actuating connections, substantially as described.

4. The combination of a movable car, a 60 nut rotatably mounted on said car, a vertically movable screw post actuated by the nut, a motor and gearing for actuating the nut, a load-carrying plate rotatably mounted on the screw, and a working platform 65 suspended from the load-carrying plate, said platform having a depending skirt provided with a cut away portion adapted to fit over the nut actuating connections, together with a guard member carried by the 70 car and arranged to guide the parts in their lowering movements, substantially as described.

5. A movable car, a nut carrying member rotatably mounted on said car, a vertically 75 movable screw arranged to be actuated by the nut, a motor and gearing for actuating the nut, said gearing having a slip member, a load carrying plate rotatably mounted on the screw, and a working platform 80 arranged below and movable with the load carrying plate, substantially as described.

6. The combination of a movable car, a vertical bearing thereon, a sleeve mounted 85 on said bearing and carrying a bevel gearing and a nut, a driving motor and gear connections for said sleeve and nut, a vertically movable screw extending through said sleeve member, nut and bearing, a load-carrying 90 plate revolvably mounted on said screw, and a working platform suspended from said plate, substantially as described.

In testimony whereof, I have hereunto set my hand.

JOHN K. FURST.
